CLAIM

The ornamental design for a combined fluorescent and incandescent lamp adapter, as shown and described.

DESCRIPTION

FIG. 1 is a front elevational view of a combined fluorescent and incandescent lamp adapter, showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom view thereof;

FIG. 7 is a front perspective view thereof, the fluorescent and incandescent lamps being shown in broken lines for illustrative purposes only.
